FRANK E. LEWIS, OF EAST PITTSBURGH, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed June 25, 1927. Serial No. 201,419.

My invention relates to motor-control systems and has particular reference to control systems for elevators, hoists and similar apparatus.

5 An object of my invention is to provide a control system for elevators wherein the starting of the car is under the control of an attendant on the car and the stopping of the car is under the control of persons desiring to use the car.

Another object of my invention is to provide a control system for elevators wherein the car is automatically stopped in response to push-buttons operated by persons desiring 15 to use the car, the buttons being either on the car or at the landings and wherein the car is started, after each stop, by a manual operation performed by an attendant on the car.

20 Another object of my invention is to provide a control system, as described in the preceding paragraph, wherein the stopping of the car is under the control of relays operated by the persons desiring to use the car and wherein the relays are maintained operative until after the car leaves the floor for which such relay has been operated.

Another object of my invention is to provide a control system for a bank of elevators 30 of the type wherein the stopping of the cars is under the control of persons desiring to use the elevators, wherein the starting of each car is under the control of an attendant on the car and wherein the first car to approach a floor at which a passenger desires to use the elevator will be caused to stop.

Another object of my invention is to provide a control system of the type described in the preceding paragraph, wherein floor 40 lanterns or other signals will be caused to be operated as the car approaches the floor preparatory to stopping thereof.

Another object of my invention is to provide a control system for elevators wherein 45 floor lanterns will be illuminated at the floors at which the car is to stop, only at such times as the car is within the distance required for deceleration in order to stop at the corresponding floor.

50 Another object of my invention is to provide a control system for elevators of the high-speed type wherein the elevator is prevented from attaining its high-speed opera-

tion when making a run of only a single floor.

55 My invention is described with reference to the accompanying drawing wherein Figures 1 and 2 are jointly diagrammatic views of the control circuits and apparatus embodied in my invention, as applied to two elevator cars.

Referring to the drawing, an elevator car C, suspended in the usual manner by a cable CA, is illustrated as operating between a plurality of floors respectively designated as 1st floor, 2nd floor, 3rd floor and 4th floor. While only four floors are shown, it is obvious that my system may be applied to elevators operating between any number of floors. A pair of push buttons are mounted 65 at each of the landings, intermediate the terminal floors, one for up travel and one for down travel. The "up" and "down" buttons for the second floor are respectively designated as 2U and 2D, while those for the third floor are designated as 3U and 3D.

70 Associated with the respective push-buttons are push-button relays 3UR, 3DR, 2UR and 2DR, respectively. Also associated with the respective push-buttons are reset relays 75 3US, 3DS, 2US and 2DS, respectively, for resetting calls registered by actuation of push button relays 3UR, etc., by restoring these relays to normal when such calls are answered, as well as restoring the signals, 80 hereinafter described, to their normal de-energized condition.

85 Push-buttons C2 and C3 for the respective intermediate floors are mounted on the car C. A floor selector FS for car C is mounted 90 at any suitable point, for example, in the pent-house or in the elevator shaft, and is provided with a set of "up" contact segments U and a set of down contact segments D, mounted upon a suitable base (not 95 shown) and traversed by a movable arm A operable in accordance with movements of the elevator. The movable arm A carries a series of brushes, AU, BU, etc., adapted to bridge the spaces between the contact segments. The floor selector FS may be similar to those ordinarily used in elevator signal systems, wherein the movable arm is operated by a screw S driven by some part of the elevator-operating mechanism for car C. 100 The frictional engagement between the arm 105

A and the screw S causes the arm to bear upon one of the sets of contact segments and to be lifted from engagement with the other set of contact segments when the elevator is 5 travelling in one direction, and the reverse of this arrangement obtains when travelling in the opposite direction.

The arrangement of the contact segments on the floor selector comprises a grouping 10 of the segments for each direction into four groups, (each group bridged by suitable brushes on the arm A), respectively designated as AU, BU, CU and EU. The group AU controls the automatic stopping of the 15 car from the floor push-buttons 2U and 3U and includes a continuous contact strip AU' and a contact segment for each of the floors served by the elevator, in the instance shown being designated as 3AU and 2AU. The 20 group BU controls the stopping of the car from the car push-buttons C2 and C3, and comprises a continuous strip BU' and segments 3BU and 2BU. The group CU controls the resetting of the push-button relays 25 2UR and 3UR and comprises a continuous strip CU' and segments 3CU and 2CU. The EU group comprises two contact segments of equal length for each of the floors and respectively designated as 3EU, 2EU and 4EU. 30 This group, it will be noted, includes a set of contact segments for the terminal floor in addition to those for the intermediate floors. The function of this group of contacts is to operate the floor lanterns L2U, and L3U, etc., 35 ordinarily used to indicate to waiting passengers which of the elevators in a bank is to stop for them.

The "down" side of the floor selector FS comprises a duplicate of the groups of "up" 40 contact members previously described, except for a reversal of the order of the contact members and a slight change in the relative positioning of the various groups to compensate for the different direction in which 45 the car approaches the floor.

A series of dotted lines numbered, respectively, 1', 2', 3', and 4' are shown upon the floor selector FS to indicate the position of 50 the movable arm with reference to the contact segments, which position corresponds to the position of the elevator with reference to the floors between which it operates.

The control system for the elevator is of 55 the automatic inductor-landing type described in the copending application of E. M. Bouton, Serial No. 731,921, filed Aug. 14, 1924, and assigned to the Westinghouse Electric and Manufacturing Company comprising a suitable motor (not shown) controlled 60 through the agency of an "up" direction switch 1 and a "down" direction switch 2, operated by a car switch CS mounted upon car C. The operation of the elevator-control 65 system may be best described with reference to an assumed operation.

Assuming that the elevator is at the first floor, the attendant on the car moves the car-switch handle CS' to the left, completing a circuit for the "up" direction switch 1 extending from line conductor L1 through conductors 10 and 11, contact members of a door relay 12, conductor 13, the coil of "up" direction switch 1, conductors 14 and 15, contact members 16 and 17, bridged by the contact segment 17 of the car switch CS, and conductors 19, 20 and 21 to line conductor L2. "Up" direction switch 1 operates to close its contact members 1e which are in circuit with the elevator hoisting motor (not shown), and the car will be caused to start upwardly. 70 80

As the car starts upwardly in response to the operation of the "up" direction switch 1, a circuit is completed for a speed relay 22 which operates to insert resistance in circuit with the motor field windings, or in any other suitable manner, to cause the elevator to operate at high speed. This circuit extends from line conductor L1 through conductors 10 and 23, the contact members of a switch UL (preferably of the limit-switch type), conductor 24, contact members 1a, conductor 25, normally closed contact members 26b of a relay 26, conductors 27 and 28, the coil of the speed relay 22, conductors 29 and 30, contact members 31a of a speed-responsive relay 31, conductor 32, thence, in series, through the normally closed contact members 33b, 34b, 35b, 36b, and thence by way of conductors 37 and 21 to line conductor L2. 90 95

Connected in parallel relation to the coil of the relay 22 is the coil of a landing switch 38. This landing switch may be of the inductor-relay type or of the type commonly used in connection with push-button-controlled elevator systems, comprise a contact member 38a which may be moved to closed-circuit position either by the energization of a coil 38b or by the depression of a cam roller 38c. The landing-switch structure is mounted upon some suitable portion of the elevator car C, such as indicated by reference numeral 38' upon the top of the car C in the drawing. The cam roller 38C contacts with a plurality of cams 39, 40, 41, 42, 43 and 44 mounted adjacent to the several floors served by the elevator. The usual operation of the switch 38 is such that the coil is energized at all times except when the car is to make a stop at a floor and the speed switch has been opened to slow down the car. As indicated by the parallel connection of the coils of the speed switch 22 and the landing switch 38, the speed will be reduced and the roller 38C will drop upon one of the cams 39, 40, 41, 42, 43 and 44, dependent upon the floor approached by the elevator. The effect of the engagement of the cam and roller will be to maintain the landing-switch contact members 38a closed until the roller 38C passes off the cam, at 100 105 110 115 120 125 130

- which time the contact members 38a will be separated.
- The contact members 38a complete a self-holding circuit for the direction switch 1 or 5 switch 2 (dependent upon the direction in which the car is travelling), maintaining the elevator motor operative until the car arrives at an exact level with the floor. This circuit may be traced from line conductor L1, 10 through conductors 10 and 11, contact members of the relay 12, conductor 13, coil of the relay 1, conductors 14 and 45, contact members 1c, conductors 46 and 47, contact members 38a of the landing switch 38, and conductors 48 and 21 to line conductor L2. As soon as this self-holding circuit is complete, the attendant on the car may return the car switch CS to its central or off position, and the car will continue to move upwardly.
- 20 Assume now that a person desiring to travel upwardly from the second floor operates the push-button 2U at that floor. The operation of this button will complete a circuit for the push-button relay 2UR extending from line conductor L1 through conductor 25 50, contact members of push-button 2U, conductor 51, the coil of relay 2UR, conductor 52, contact members or reset relay 2US and conductors 53 and 21 to line conductor L2. Push-button relay 2UR completes a self-holding circuit which extends from line conductor L1 through conductor 30 54, contact members 2URa and conductor 55 and thence through the coil 2UR to line conductor L2, as previously described. Contact members 2URb partially complete a circuit for the "up" floor lantern L2U for the second floor, and contact members 2URc partially complete a circuit for the relay 36.
- 40 As the car starts upwardly from the first floor, the brush AU of the floor selector arm A is in engagement with the contact strip AU' and the contact segment 2AU. Thus, a circuit for the relay 36 is immediately closed, upon the operation of the relay 2UR, extending from line conductor L1 through conductors 54 and 56, contact members 2URc, conductors 57 and 58, contact segment 2AU, brush AU contact strip AU', conductor 59, the coil of relay 36, and conductors 60, 61 and 21 to line conductor L2.
- 45 The brush EU, at this instant, also connects the two contact segments 2EU, thus completing the circuit for the second floor "up" floor lantern L2U. This circuit extends from line conductor L1 through conductors 54, 56 and 65, contact members 2URb, conductors 66 and 67 contact segments 2EU, conductor 68, floor lantern L2U, and conductors 69 and 70 to line conductor L2. The floor lantern is illuminated to indicate to the waiting passenger that the car associated with this lantern will be the one which will stop for him.
- 50 While only two elevators are shown, it is to be understood that my system is applicable to a bank of any number of elevators in which a set of floor lanterns, individual to each of the elevators, are usually provided. Thus, it is desirable to indicate which one of several elevators is to stop at the floor. It will also be noted that the conductors 68 and 58 may be common to a number of elevators in the bank, as indicated by the arrow-heads placed upon the lower ends of these conductors.
- The energization of the relay 36, as described, breaks the circuit for the speed relay 22 and the landing switch 38 by its contact members 36b, and closes a circuit 80 energizing the "slow-down" inductor relays 71 and 72. This circuit extends from line conductor L1 through conductors 10 and 75, contact members 36a, conductors 76 and 77, the coil of the inductor relay 71, conductors 78 and 79, contact member 80 on the car switch CS and thence through the contact segment 17, contact member 18 of the car switch CS, and conductors 19, 20 and 21 to line conductor L2.
- 85 The speed relay 22 is provided with a self-holding circuit extending from the coil 22, through conductors 29, 30 and 81, contact members 22a, conductor 82, normally-closed contact members 71' of the relay 71, the normally-closed contact members 130 of the relay 72, and conductors 84, 20 and 21 to line conductor L2. Thus, the opening of the contact members 36b will not cause the immediate deenergization of the relay 22. 90 However, as the car approaches the "slow-down" zone for the second floor, the inductor relay 71, now energized, passes an inductor plate 85 and operates to open its normally closed contact members 71'. The opening of the contact members 71' deenergizes the speed relay 22 and the landing switch 38, thus reducing the speed of the car and permitting the roller 38c to be engaged by cam 40. As the car continues toward the second floor, the roller 38c moves off the cam 40, and the car is brought to an accurate stop, level with the second floor.
- 100 It is desirable to have the floor lamp L2U, remain illuminated until the car starts to leave the floor. This is accomplished, in my system, by extending the floor-lamp contact segments 3EU, 2EU etc. to a point which represents the position of the car at a level with the corresponding landing and by maintaining the push-button relay, associated with this floor, in operative condition until the car leaves the floor. The restoring of the push button relay is accomplished by the energization of the associated reset relay. 110 For example, in our assumed operation of the second floor "up" stop, the push-button relay 2UR remained energized through its self-holding circuit, leading through the reset relay 2US. The circuit for the relay 115 120 125 130

2US extends through normally closed contact members 31b of the speed-responsive relay 31.

The relay 31 is connected across the armature MA of the hoisting motor (shown only as a circle with the reference character MA), and is designed to be picked up only at such times as the hoisting motor is operating at high speed but will remain energized until 10 the car comes to a complete stop. Thus, as the car passes a floor for which a button has been operated, without stopping (such as when the button was actuated after the car had passed the beginning of the slow-down 15 zone for that floor), the contact made by the brushes CU and the contact segment 2CU would not effect a restoration of the push-button relay, since the restoring circuit is held open by relay 31. The relay 2UR 20 would then function to stop the next car to approach the floor.

When, however, the car stops at the floor (as in the assumed operation) and then restarts, the closing of the direction switch 1 25 or the direction switch 2 will energize the corresponding reset relay, since, at this time, the speed-responsive relay 31 has its contact members 31b closed. This circuit extends from line conductor L1 through conductors 30 86, and 88, coil of relay 2US, conductor 89, contact segment 2CU, continuous contact strip CU', conductor 90, contact members 1d, conductors 91 and 92, contact members 31b, and conductors 93 and 21 to line conductor 35 L2.

The attendant on the car next opens the second floor door and the passenger enters the car. While the doors are open, the elevator car is prevented from starting by the 40 deenergization of the relay 12, the circuit for which leads through the door and gate switch indicated by legends. When the attendant again closes the doors, the relay 12 is energized by way of a circuit which 45 extends from line conductor L1 through conductor 186, the gate and door switches, conductor 187, coil of relay 12 and conductors 188 and 21 to line conductor L2. The attendant may then again start the car on its 50 upward movement by proper operation of the car switch CS, as described, before the start from the first floor.

As the car starts upwardly from the second floor, the "up" direction switch 1 and the 55 speed relay 22 will operate to start and speed up the elevator as previously described. The car will continue upwardly, stopping at the other floors for which "up" buttons have been operated, as described for the second 60 floor stop. As the car approaches its upper limits of travel, a cam 100 mounted on the elevator car will engage and open the contact members of the switch UL. The opening of switch UL will open the circuit to the "up" 65 direction switch and to the speed switches to

cause the car to stop at the upper terminal, independently of the operation of any push-buttons at the terminal floor.

At the upper terminal the brush EU of the floor selector FS will complete a circuit 70 for the floor lantern L4D extending from line conductor L1 through conductors 100' and 101, contact segments 4EU, conductor 102, floor lantern L4D, and conductors 103 and 70 to line conductor L2. 75

The attendant on the car now moves the car-switch handle CS to the right, completing a circuit for energizing the "down" direction switch 2, and the car starts downwardly in the manner described for upward 80 movement.

Assume that a passenger entering a car at the upper terminal or fourth floor desires to leave the car at the second floor and informs the attendant of his desire. The attendant 85 operates the button C2 on the car, partially completing a circuit for the relay 33. A "hold-down" coil 105 is mounted on the car adjacent the push-buttons C2 and C3 for the purpose of maintaining these push-buttons in 90 their depressed positions when operated by the attendant. The circuit for this coil extends from line conductor L1 through conductors 10, 11 and 106, contact members 107c, conductors 108 and 109, the "hold-down" 95 coil 105, and conductors 110, 20 and 21 to line conductor L2.

The car proceeds downwardly until the brush BD of the movable arm A of the floor selector FS bridges the continuous contact strip BD' and contact segment 2BD. At this time, a circuit will be completed for the relay 33, extending from line conductor L1 through conductors 10 and 120, contact members of push-button C2, conductors 121 and 122, contact segment 2BD, brushes BD, continuous contact strip BD', conductor 123, the coil of relay 33, and conductors 124, 61 and 21 to line conductor L2. The relay 33 energizes the inductor relay 72 by way of a circuit which extends from line conductor L1 through conductors 10, 11, 75 and 125, contact members 33a, conductors 126 and 127, the coil of the inductor relay 72 and thence, by way of conductor 128 and the central contact member 80 of the car switch CS, to line conductor L2, as traced for the inductor relay 71. 110

The car approaches the second floor and the inductor plate 129 operates relay 71 to 120 open (by its contact members 130) the holding circuit for the "down" direction switch 2 in the same manner as described for the operation of the relay 71. The car is thus brought to a stop level with the second floor 125 landing. After the exit of the passenger, the attendant again operates the car switch CS to cause the car to proceed on its downward trip, as previously described.

Relays 26 and 107 are designated as "up" 130

and "down" relays, respectively, and are controlled by a pair of limit switches UL and DL, engageable by cams 100 and 111, respectively, as the car approaches the upper 5 and lower limits of travel. The function of these relays is twofold. The first function is to insure the deenergization of the "hold-down" magnet coil 105 and the subsequent release of the push-buttons C2 and C3 on 10 the car at the end of each up or down trip of the elevator. The second function is to prevent the car from travelling at high-speed in the case of a reversal of the car before it has completed a full up or down 15 trip. The circuits for the speed relay 22, and the landing switch 38 pass through normally closed contact members of the relays 107 and 26 (as described in the tracing of these circuits.)

20 Assuming, for example, that the car is operated on a normal up trip, the relay 107 will be energized by way of a circuit which extends from line conductor L1 through conductor 100', the normally closed contact 25 members of a switch UL, conductor 112, the contact members of an "up" release, button 113 (mounted on the car), conductor 114, the normally closed contact members 26a of relay 26, conductor 115, the coil of 30 relay 107 and conductors 116 and 21 to line conductor L2. The relay 107 will remain energized until the car arrives at its upper limit of travel, and operates switch UL, at 35 which time the relay 107 is deenergized and the relay 26 will be energized.

Suppose that, during the upward trip, the attendant discovers that his car has passed a floor at which it is desired to stop the car. He may reverse the car switch CS and bring 40 the car back to the floor which was passed. That is, the car will reverse and travel downwardly at low speed only, since the circuit for high-speed operation is open at the contact members 107b. Thus, the car 45 will travel at slow speed until it arrives adjacent the next lower floor, at which time the landing switch 38 will operate to stop the car level with the floor.

In modern high-speed elevators, operating 50 at speeds between 600 and 900 feet per minute, the slow-down zone for any floor will extend through a distance which is greater than the distance between adjacent floors. Under these conditions, if a car is 55 standing at one floor, for example, the second floor, when a button is operated for the third floor, the car will not have sufficient time, in passing between the adjacent floors, to attain high speed and then slow down 60 for the third floor. To allow for this condition, the circuits for the high-speed switch 22 and the landing switch 38 lead through the contact members of all of the relays 33, 34, 35 and 36 and, in the event that any one 65 of these relays is energized, as by the oper-

ation of one of the signal buttons at the floors or on the car, to cause the car to stop at the next adjacent floor, the speed relay is prevented from closing. Thus, the car will proceed to the next floor at slow speed only and will stop thereat in consequence of the operation of the landing switch 38.

It is thus seen that I have provided a control system which combines, in a single 70 floor selector, the functions of controlling the stopping of the car in response to passenger-operated push-buttons, the restoration of the passenger-operated buttons, and the illumination of appropriate floor-landing lanterns 75 at the floors, as the car prepares to stop thereat. My system also provides for permitting high-speed elevators having overlapping "slow-down-zones" to receive signals for, and to stop at, adjacent floors and 80 wherein the elevator will automatically operate at the proper speed to make such adjacent stops.

Figure 2 illustrates the manner in which 85 additional cars may be connected to the floor 90 push buttons 3U, 3D etc. and other associated relays whereby the control system described herein may be applied to a bank of elevators. Figure 2 illustrates a car B having its controlling circuits and devices identical with those for car C. The connection 95 of the control circuits for car B to those herein described for car C comprises merely the paralleling of conductors in groups 120, 121 and 122, respectively, to the corresponding 100 contact strips and segments on floor selector FS' associated with car B and, in like manner, to the floor selectors of as many other cars as may be in the bank. It will be observed that the conductors in group 120 are 105 connected in parallel relation to the contact segments 3CU and 2CU to supply current to resetting of restoring relays 3US and 2US, respectively, and, in like manner, to the corresponding contact segments on the "down" 110 side of the floor selector FS to complete circuits for resetting relays 3DS and 2DS, respectively. Conductors 121 are connected in parallel relation with contact segments 3AU, 2AU, 2EU and 3EU, respectively, for supplying current to respective contact segments 115 on the floor selectors for other cars in the bank when the associated push-button relays 3UR etc. have been energized. Conductors in group 122 are connected in parallel relation with contact segments 3AD, 2AD, 3ED and 2ED for connecting similar contact segments on the floor selectors for each of the cars in the bank to control their respective 120 circuits when the push-button relays 3DR and 2DR are energized.

It will be readily observed, therefore, that 125 my system is applicable to a plurality of elevator cars constituting a bank of adjacent elevators.

My system also provides for the automatic stopping of the car from within it, as by the push-buttons C2 and C3, so connected that only one set of buttons is necessary for 5 both up and down movements of the elevator.

The embodiment of my invention disclosed herein, is merely illustrative, the apparatus and circuits involved being capable of adaptation to varied conditions of service involving different numbers of elevators and an indefinite number of floors served by the elevators. My invention is applicable to any type of control systems for elevator motors, 10 such as the Ward-Leonard type, or the rheostatic type of control. Therefore, I do not desire to be limited to the details of the system shown, except as defined in the appended 15 claims.

20 I claim as my invention:

1. In a control system for elevators, a car operated between two terminal floors, a plurality of intermediate floors, multi-speed means for moving said car in either direction, means for controlling the direction and 25

speed of said moving means, and means responsive to the initial operation of said moving means in one direction for preventing said moving means from operating at greater than its lowest speed in reversed movement 30 until said car has reached the terminal floor in the first direction.

2. In a control system for elevators, a car operated between two terminal floors and a plurality of intermediate floors, multi-speed 35 means for moving said car in either direction, means for controlling the direction and speed of said moving means, and means responsive to the initial operation of said moving means in one direction for preventing 40 said moving means from operating at greater than its lowest speed in reversed movement until said car has reached the terminal floor in the first direction, and means for automatically stopping said elevator at the landing next approached in said reverse direction. 45

In testimony whereof, I have hereunto subscribed my name this 21st day of June, 1927.

FRANK E. LEWIS.
